NOVEL SULFONYLUREAS

Jack Mills and Frederick J. Marshall, Indianapolis, Ind., assignors to Eli Lilly and Company, Indianapolis, Ind., a corporation of Indiana

No Drawing. Filed Nov. 30, 1961, Ser. No. 156,159
2 Claims. (Cl. 260—553)

This invention relates to certain novel hypoglycemic agents of the sulfonylurea class and to the control of diabetes mellitus therewith.

The compounds provided by this invention can be represented by the formula

wherein R is 2-bicyclo[2.2.1]heptyl or 2-bicyclo[2.2.1]heptylmethyl. The compounds defined by the above formula are N-p-ethylphenylsulfonyl-N'-2-bicyclo[2.2.1]heptylurea and N-p-ethylphenylsulfonyl-N'-2-bicyclo[2.2.1]heptylmethylurea.

The incorporation of the bicyclo[2.2.1]heptyl or bicyclo[2.2.1]heptylmethyl group into certain sulfonylureas confers an unexpectedly high order of antidiabetic efficacy upon the compounds. This is advantageous not only because it makes possible the use of doses of the compounds lower than those employed with other clinically useful sulfonylureas, but also because it tends to decrease the frequency and severity of the side effects which may be manifested in some degree in some cases with this class of therapeutic agents.

Various methods known in the art can be employed for the preparation of the compounds of this invention. One preferred method comprises the interaction of ethyl-N-p-ethylphenylsulfonylcarbamate with 2-bicyclo[2.2.1]heptylamine or 2-bicyclo[2.2.1]-heptylmethylamine to form a salt and the pyrolysis of the salt by heating at its decomposition point. The latter step is preferably carried out in an inert solvent such as toluene, xylene or the like. The desired product is readily recovered from the reaction medium by employing standard techniques.

Other methods may also be employed for the preparation of the instant compounds. Thus, for example, 2-bicyclo[2.2.1]heptylisocyanate or 2-bicyclo[2.2.1]heptylmethylisocyanate can be treated with p-ethylphenylsulfonamide in the presence of an alkali-metal carbonate to produce the desired sulfonylurea. Additionally, there are available the methods employing the reaction of p-ethylphenylsulfonamide with 2-bicyclo[2.2.1]heptylurethane or 2-bicyclo[2.2.1]heptylmethylurethane and the reaction of p-ethylphenylsulfonamidoisocyanate with 2-bicyclo[2.2.1]heptylamine or 2-bicyclo[2.2.1]heptylmethylamine. Still another method utilizes the pyrolysis in the presence of the appropriate amine of a diphenylsulfonylurea prepared from p-ethylphenylsulfonamide and phosgene.

The cationic salts of these compounds can be prepared by treating the sulfonylureas with a suitable base or basic salt, as for example ammonium hydroxide, magnesium hydroxide, potassium hydroxide, sodium carbonate, and the like. Among the preferred nontoxic cationic salts are the sodium, potassium, calcium, magnesium, and ammonium salts.

The sulfonylureas of this invention and their nontoxic cationic salts are white, high-melting solids, the former

2

crystallizing readily from ethanol. The sulfonylureas are soluble in the common organic polar solvents, while their salts are soluble to some extent in aqueous-organic solvent mixtures.

The compounds of this invention are orally effective hypoglycemic agents and are therefore useful in the treatment of diabetes. Thus, the blood sugar level of depauperate dogs can be regulated by the oral administration to these animals of the drugs. Of even greater significance is the fact that oral administration of daily doses of between about 50 mg. and 1500 mg. of the compounds will provide adequate control of the blood sugar levels of diabetic humans.

Any of the customary oral dosage forms are suitable for the administration of the compounds of this invention, but compressed tablets or filled capsules, containing the desired amount of drug together with the customary pharmaceutical excipients, are preferred. Thus, for example, a mixture of starch, magnesium stearate, granular gelatin and N-p-ethylphenylsulfonyl - N'-2-bicyclo[2.2.1]heptylurea can be compressed into scored tablets of a size such that each tablet contains 100 mg. of the active medicament.

The operation of the invention is illustrated in the following specific examples.

Example 1

A toluene suspension of the N-p-ethylphenylsulfonylcarbamate salt of 2-bicyclo[2.2.1]heptylamine was prepared by mixing 55 g. of ethyl N-p-ethylphenylsulfonylcarbamate and 40 g. of the amine in 500 ml. of toluene. The mixture was heated at reflux temperature for five hours in order to pyrolyze the carbamate salt and form N-p-ethylphenylsulfonyl-N'-2-bicyclo[2.2.1]heptylurea. The reaction mixture after being cooled was diluted with ether and extracted with 10 percent ammonium hydroxide. The basic extract was chilled in an ice bath and acidified by adding dilute hydrochloric acid. The product was extracted into ether, the ether layer was dried, and the ether was removed under vacuum. The residue was recrystallized from ethanol to give N-p-ethylphenylsulfonyl-N'-2-bicyclo[2.2.1]heptylurea melting at 129-31° C.

Analysis.—Calc.: C, 59.59; H, 6.88; N, 8.69. Found: C, 59.68; H, 6.67; N, 8.43.

Example 2

A parallel procedure employing 2-bicyclo[2.2.1]heptylmethylamine with ethyl N-p-ethylphenylsulfonylcarbamate produced N-p-ethylphenylsulfonyl - N'-2-bicyclo[2.2.1]heptylmethylurea melting at 163-5° C. after recrystallization from ethanol.

Analysis.—Calc.: C, 60.65; H, 7.19; N, 8.33. Found: C, 60.45; H, 7.20; N, 8.23.

Example 3

A solution of 0.5 g. of N-p-ethylphenylsulfonyl-N'-2-bicyclo[2.2.1]heptylurea in chloroform was shaken vigorously with a slight excess of a 10 percent aqueous sodium carbonate solution. The sodium salt of N-p-ethylphenylsulfonyl-N'-2-bicyclo[2.2.1]heptylurea was precipitated and was isolated by filtration as a white amorphous solid.

We claim:

1. A compound selected from the group consisting of compounds of the formula

wherein R is 2-bicyclo[2.2.1]heptyl, and the salts thereof with nontoxic cations.

2. N-p-ethylphenylsulfonyl-N'-2-bicyclo[2.2.1]heptyl-
urea.
